[57] CLAIM

The ornamental design for a seat, as shown and described.

DESCRIPTION

FIG. 1 is a front perspective view of a seat in the form of a chair showing my new design;

FIG. 2 is a left side perspective view of the seat shown in FIG. 1;

FIG. 3 is a right side perspective view of the seat shown in FIG. 1;

FIG. 4 is a rear perspective view of the seat shown in FIG. 1;

FIG. 5 is a top perspective view of the seat shown in FIG. 1;

FIG. 6 is a bottom perspective view of the seat shown in FIG. 1;

FIG. 7 is a front perspective view of a seat in the form of a loveseat showing my new design;

FIG. 8 is a left side perspective view of the seat shown in FIG. 7;

FIG. 9 is a right side perspective view of the seat shown in FIG. 7;

FIG. 10 is a rear perspective view of the seat shown in FIG. 7;

FIG. 11 is a top perspective view of the seat shown in FIG. 7; and,

FIG. 12 is a bottom perspective view of the seat shown in FIG. 7.

The broken lines shown in the drawings represent stitching.
